No. 851,258.

PATENTED APR. 23, 1907.

H. J. SHARP.
BABY WAIST.
APPLICATION FILED SEPT. 4, 1906.

UNITED STATES PATENT OFFICE.

HANNAH J. SHARP, OF BILLINGS, MONTANA.

BABY-WAIST.

No. 851,258.

Specification of Letters Patent.

Patented April 23, 1907.

Application filed September 4, 1906. Serial No. 333,163.

To all whom it may concern:

Be it known that I, HANNAH J. SHARP, a citizen of the United States, residing at Billings, in the county of Yellowstone and State of Montana, have invented certain new and useful Improvements in Baby-Waists, of which the following is a specification.

This invention relates to new and useful improvements in nether garments and it particularly pertains to a waist for infants.

The invention aims as a primary object to provide a waist, which can readily be made of varying sizes in use, in accordance with the degree of growth of the infant.

The invention further aims to provide a nether garment which can be easily and quickly put on and taken off, and in which all positive fastening means are eliminated.

The invention finally aims to provide a garment of the type set forth which shall be comfortable and will not bind and which in all other respects will be practical and efficient in use.

The detailed construction will appear in the course of the following description in which reference is had to the accompanying drawings forming a part of this specification, like numerals designating like parts throughout the several views, wherein,

Figure 1 is a developed plan view of a nether garment constructed in accordance with my invention. Fig. 2 is a plan view of the garment in position for use.

In the practical embodiment of my invention I employ a body portion 1 of suitable conformation and provided with arm holes 2. Mounted on each side of the body portion 1 are laterally extending straps 3, which are connected with said body portion by elastic strips or webs 4. The straps 3 have secured to their extremities strings or ties 5. For the purpose of facilitating the conformation of the waist to the body of the infant upon which it is worn, the body portion 1 is provided on one side thereof, and preferably beneath the adjacent arm hole 2 with a sub-

stantially vertical slit 6 through which one of the straps 3 is designed to be projected. Depending from the lower edge of the body portion 1 at suitably arranged points are tabs 7 secured to said body portion by elastic strips or webs 8. The tabs 7 are designed to serve as a support for other nether garments by virtue of fastening means of approved form as will be readily understood. The exposed edges of the various elements of the garment are reenforced by braiding 9.

In practical use the garment is worn as shown in Fig. 2. One of the straps 3 is inserted through the slit 6 and the other of said straps is brought around upon the outside of the waist and the two straps have their strings 5 tied in back as indicated. In this manner by tightening or loosening the straps 3, the size or span of the body portion 1 can be readily adjusted. The provision of the elastic strips or webs 4 and 8 prevents the waist from binding and being uncomfortable.

While the elements herein shown and described are well adapted to serve the functions set forth it is obvious that various minor changes may be made in the proportions, shape and arrangement of the several parts without departing from the spirit and scope of the invention as defined in the appended claims.

Having fully described my invention claim:

A garment of the character described comprising a body portion provided with arm holes and with a vertical slit beneath one of said arm holes, said body portion being provided on each side thereof with laterally extending straps united thereto by strips of elastic fabric.

In testimony whereof I affix my signature in presence of two witnesses.

HANNAH J. SHARP.
